CLAIM

The ornamental design for a support pan, as shown and described.

DESCRIPTION

FIG. 1 is a top perspective view of a support pan showing the new design;

FIG. 2 is a top view of the support pan of FIG. 1;

FIG. 3 is an end view of the support pan of FIG. 1, with the opposing end view being a mirror image thereof;

FIG. 4 is a side view of the support pan of FIG. 1, with the opposing side view being a mirror image thereof; and,

FIG. 5 is a bottom view of the support pan of FIG. 1. The broken lines shown in the figures depict portions of the support pan that form no part of the claimed design.

1 Claim, 3 Drawing Sheets(56)
